UNITED STATES PATENT OFFICE.

JOHN S. WORTH, OF COATESVILLE, PENNSYLVANIA, ASSIGNOR TO WORTH BROS., OF COATESVILLE, PENNSYLVANIA, A FIRM.

CONTINUOUS HEATING-FURNACE.

1,374,132.

Specification of Letters Patent

Patented Apr. 5, 1921.

Application filed March 20, 1919. Serial No. 283,697.

To all whom it may concern:

Be it known that I, JOHN S. WORTH, a citizen of the United States, and a resident of Coatesville, county of Chester, State of Pennsylvania, have invented certain Improvements in Continuous Heating-Furnaces, of which the following is a specification.

My invention relates to certain improvements in continuous furnaces for heating billets, plates, &c.

One object of the invention is to improve the construction of furnaces of this type by using a continuous beam, or a series of beams; extending through the furnace and having means for cooling the beams.

A further object of the invention is to provide means for lifting the beams, said means being entirely outside of the furnace.

20 The invention also relate to details described hereinafter.

By my improved construction a higher heat can be attained than in ordinary furnaces of this type.

25 In the accompanying drawings:

Figure 1 is a longitudinal sectional view of my improved heating furnace on the line 1—1, Fig. 2;

Fig. 2 is a sectional plan view on the 30 line 2—2, Fig. 1; and

Fig. 3 is a transverse sectional view on the line 3—3, Fig. 1.

Referring to the drawings, 1 is the furnace supported on arches 2, which may

35 form part of a regenerating structure so as to heat the furnace to the proper degree. 2

is the bed of the furnace having a series of longitudinal slots 3 therein extending the full length of the furnace. Mounted in each

40 of these slots is a rectangular hollow beam 4, in the present instance, although the cross section of the beam may be varied, as desired. The beam is of greater length than the furnace and projects from both ends of

45 the furnace structure 1, as clearly shown in Fig. 1. These beams 4 carry on their upper surface fire brick 5, or other equivalent material for protecting the beams. These fire brick also form a continuation of the fixed

50 bottom of the furnace so as to provide an uninterrupted hot surface. The beams, as stated above, are hollow and are connected to circulating pipes at each end, as at 6 and

7 communicating with a water supply system, or an air supply system, so that the 55 beams can be cooled by the circulation of water or air.

In the present instance, there are four beams in the furnace and they extend beyond each end thereof. I locate on the outside of the furnace at each end lifting means and I also provide means at one end of the furnace for reciprocating the beams so that a billet, or plate, mounted on a beam, or beams, at one end of the furnace will be carried into the furnace and intermittently fed through the furnace and discharged at the opposite end. I have shown four beams divided into pairs and each pair is independently operated.

At one end of the furnace are two shafts 10 and at the other end two shafts 10^a. Each shaft is adapted to suitable bearings. On the shafts are arms 9 carrying rollers 8 flanged, in the present instance. The rollers are located under the beams, as shown, so that any rotary motion imparted to the shaft will raise the beams so that their upper surfaces will be above the bottom of the furnace and, consequently, will lift a 80 billet, or plate, off of the furnace bottom. When a longitudinal movement is imparted to the beam, or beams, the billet, or plate, will be moved forward and when the beams recede the billet, or plate, will rest again 85 on the bottom of the furnace in an advanced position.

Each shaft 10 has an arm 11 to which is attached a rod 12 connected to a cross head of a piston rod adapted to a cylinder 13. In 90 order that the shaft 10^a, opposite its shaft 10, may be turned simultaneously with the shaft, I provide the shaft 10 with an arm 14 and the shaft 10^a with an arm 15. The two arms are connected by rods 16 located on the 95 outside of the furnace, as shown in Fig. 2.

In order to counterbalance the beams to a certain extent, I secure to the shafts 10 and 10^a arms 17 having counterbalance weights 18. The beams are reciprocated by double 100 acting cylinders 20. In the present instance, the rod 21 is connected by a link 22 to a lever 23 pivoted at the base and slotted at its upper end to receive a pin 24, which is attached to the two beams 4—4. By this construction, the beams can be raised and low-

ered and reciprocated. Other means for imparting a reciprocating motion to the beams may be used without departing from the essential features of the invention.

5 The operation is as follows: The furnace is brought to the desired heat and the billets, ingots, or plates, are placed in position, preferably so as to be supported by, at least, two beams 4 when the beams are elevated. The 10 billets are placed on the ends of the beams on the outside of the furnace and when motion is imparted to the shafts 10 and 10^a, the beams and billets are carried into the furnace and deposited on the bottom thereof 15 and are progressively fed through the furnace as the beams are reciprocated. The several billets inside of the furnace are also moved forward. The first billet is discharged at the opposite end of the furnace. 20 The beams, which are hollow, are cooled by the circulation of water, or air, and thus the furnace can be brought to a higher heat than where the operating mechanism is located within the furnace. Furthermore, there is 25 no liability of the mechanism breaking down, due to the high heat. In case of any trouble, access can be readily had to the mechanism.

As each of the beams has its upper surface covered with fire brick, or like material, 30 the entire bottom of the furnace is kept hot and there is no likelihood of the beams warping, or sagging, due to excessive heat and the weight of the material. Any suitable 35 means may be provided for conveying the material to the beams and carrying the material away from the furnace, depending considerably upon the further treatment of the material. If, for instance, the bloom, or 40 billet, is to be rolled, then the roller table of the mill may be extended so as to receive the bloom, or billet, as it is discharged from the furnace. While I have shown a double furnace in which there are two sets of beams, 45 independently operated, these beams may be connected so as to operate in unison, if desired, in which case there will be a single shaft at each end instead of the two shafts shown. The capacity of the furnace will depend entirely upon the material to be 50 treated.

I claim:

1. The combination in a continuous heating furnace, of a furnace structure; a beam 55 extending longitudinally through the furnace and projecting beyond each end thereof; a transverse shaft at each end of the furnace; an arm on the shaft; a roller car-

ried by the arm; means for turning the two shafts in unison so as to raise the beam; a 60 pivoted lever at one end of the shaft and connected to the beam; and means for moving said lever to reciprocate the beam so that material placed on the beam will be intermittently fed through the furnace. 65

2. The combination in a continuous heating furnace, of a furnace structure; a series of beams extending longitudinally of the furnace and projecting at each end thereof; a transverse shaft at each end of the furnace; arms secured to the shaft for raising the beams above the bottom of the furnace; an arm on each shaft; a rod connecting the two arms; a third arm on one of the shafts; mechanism, outside of the furnace, for operating the shaft through said third arm; a lever on the outside of the furnace at one end thereof, said lever being connected to the beams; and means for operating the lever to reciprocate the beams. 75

3. The combination of a furnace having a series of longitudinal slots in the bed thereof; a beam located in each slot and extending beyond each end of the furnace, said beams being arranged in pairs; two transverse shafts, one beyond each end of the furnace; arms on the two shafts located under the beams; means for connecting the shafts so that they will operate in unison, said connection being outside of the furnace; power 90 mechanism for operating the shafts so as to raise the beams above the bed of the furnace; a slotted lever engaging a pin on each pair of beams; and a cylinder connected to each lever so as to move the beams in one direction when they are in the raised position and to return them when lowered. 95

4. The combination of a furnace having a bed, longitudinal slots in the bed; a longitudinal beam in each slot, said beams extending beyond the ends of the furnace; a transverse shaft beyond each end of the furnace and on the outside thereof; an arm on each shaft having rollers arranged to engage the underside of the beam and raise it above the bottom of the bed; a counterbalance mounted on the shafts and engaging one end of a beam; and means for reciprocating the lever so that the beam can be raised as it moves in one direction, or can be raised when moved in the opposite direction to reverse the feed of the material traveling through the furnace. 100

In witness whereof I affix my signature.

JOHN S. WORTH.
